UNITED STATES PATENT OFFICE

2,396,517

MEANS FOR CONTROLLING THE SUPPLY OF
FUEL TO INTERNAL-COMBUSTION EN-
GINES

William Douglas Marchant, Weybridge, England

Application July 9, 1943, Serial No. 494,050
In Great Britain July 20, 1942

4 Claims. (CL 123—119)

This invention relates to an improved system of metering for controlling the supply of combustible mixture to the combustion chamber of an internal combustion engine and has for its object to obtain parallelism of the fundamentals governing the metering and flow of air and fuel or explosive mixture.

The main factors controlling the quantity of air, gas or liquid fuel flow are:

1. The area of the restricting orifice
2. The degree of pressure employed (positive or negative) for effecting the fuel flow, and
3. The time factor, i. e. time during which fuel flow takes place.

It is suggested that unless these three fundamental factors are in parallelism or accordant throughout their range of operation, an accurate degree of air and fuel metering is not to be expected with the varying speed and varying load prevailing with internal combustion engines embodying electrical ignition.

An examination of the orthodox systems employed with internal combustion engines reveals that only two of the above factors are in parallelism, i. e. when fuel injection is employed 1 and 3 may be in parallel and with a carburetor system 1 and 2 may be in parallel. While air flow will commence the moment that the induction system is, by piston displacement, reduced below atmospheric pressure, fuel flow will not commence until a relatively lower degree of depression is obtained. This is a varying factor which depends primarily upon the controlling orifice of the fuel flow, the throttle position and the engine speed. Compensating devices have been introduced with the object of maintaining the air fuel ratio within the wide firing limits, but such devices have not been entirely satisfactory and can only be considered a crude compromise.

It is believed that the high percentage of waste in the orthodox carburetor system can be attributed chiefly to inaccurate metering or flow control and that whilst a certain quantity of fuel may have been drawn from the fuel supply by the suction stroke of a piston, a large proportion of such fuel, which to a certain degree is atomised, does not enter the combustion chamber during the said suction stroke, but remains stagnant in the induction system and will enter the cylinder in such a manner as to be of little or no useful value; under certain conditions the fuel having been reduced to a stationary condition may be carried back by what is known as a blow

back. These conditions vary with engine speeds and throttle openings.

A condition similar in effect to blow back exists in multi-cylinder internal combustion engines having an overlapping period on the inlet valve opening curves, when the negative pressure of a cylinder with inlet valve opening exceeds the negative pressure of the cylinder with the valve closing. The rear part of the charge 10 is reduced to a stationary and stagnant condition, varying with engine speed and weight of charge. These conditions may be and are often improved by sacrificing volumetric efficiency. It would appear that the latter part of the charge 15 should be free from fuel.

It has been found that if fuel is introduced into an air stream moving at a comparatively high velocity, an excellent degree of atomization may be obtained. It has also been found that it is 20 not advisable to permit fuel to enter the combustion chamber until the piston displacement is approaching its peak. It would therefore appear that the forward part of the charge should also be free of fuel.

25 It is known that the higher the depression the higher the degree of atomization. The highest point will be in the center of the piston displacement curve and also that part of the curve where over a given crank angle, the depression will be 30 approximately constant. It should therefore be possible to select the correct crank angle period or correct moment during piston displacement creating a depression to permit fuel to flow.

It has been found that both weight and quantity of a charge is to a certain extent controlled when a definite ratio between engine speed and restricted orifice or throttle opening is maintained. While forms of suction valves are often employed for attaining this object, the disadvantages of such valves are well known.

45 To obtain accurate and economic metering it is considered essential that the fuel flow line from point of fuel metering to the combustion chamber should be clear of fuel at the completion of each induction stroke; because of variations any fuel remaining within this line may not be considered as forming a part of the following metered charge.

The invention therefore comprises a new system of controlling the flow of fuel to an internal combustion engine which consists in the use of means whereby the effect of pressure positive or negative controlling the fuel flow is broken down or rendered impotent periodically, whereby fuel flow is interrupted and obtains only for a pre-

determined period, said means being operable in timed relation to the rotation of the engine. Preferably the impotency is obtained during the suction stroke of the engine.

Where it is required that a depression is broken down, this is effected preferably through the intermediary of a valve, for example a rotary sleeve valve which is opened to the atmosphere periodically in such a manner that the fuel flows only during a period which is within the ambit of the suction stroke of the engine, approximating for example an angle of 60° of the piston displacement. The valve is mechanically operated in timed relation to the rotation of the engine and becomes effective to vent the depression to atmosphere at all times other than the period during which fuel is required to flow, the venting taking place at either side of the fuel controlling orifice, in both cases the fuel flow being stopped except for a predetermined period of time during and within the angle of the displacement stroke of the piston in such a manner that a considerable increase in efficiency results over known systems of fuel control.

In order that the invention may be clearly understood, reference is directed to the accompanying drawings wherein—

Figure 1 is a side elevation partly in section showing a fuel supply apparatus and control mechanism therefore in accordance with the invention;

Figure 2 is an end view of Figure 1, partly in section and looking in the direction of the arrow;

Figure 3 is a sectional elevation of the upper part of Figure 1 on an enlarged scale with a slight modification of the position of conduit 15.

Figure 4 is a view at right angles to Fig. 3 illustrating detail;

Figures 5 illustrates diagrammatically a further application of the invention.

Figures 6 and 7 being part views of Fig. 5 illustrating different positions of the parts.

Referring to the drawings, more particularly Figs. 1 to 4, 8 indicates generally the body of the metering and mixing device hereinafter termed "the apparatus," 9 being the fuel chamber thereof, 10 the air inlet and 11 the outlet, 12 being a flange by means of which it is connected to the inlet manifold of an internal combustion engine in the usual manner. The apparatus is in communication with a valve chamber 13 housing a rotary valve or rotor 14 which controls the period at which depression is permitted to cause fuel flow through a metering orifice, air at atmospheric pressure being available at other times by way of a conduit 15 to a jet chamber 16 disposed below and forming part of the main body 8 of the apparatus. The apparatus is provided with a variably controlled orifice or jet 17 through which the quantity of fuel is controlled by means of a tapered needle 18 forming part of a spindle 20 which is reciprocable in conjunction with a throttle slide 21 which controls the flow of air through the inlet 10. The slide 21 is connected by means of an arm 22 to the spindle 20 by means of a peripherally grooved collar 23 which is operatively associated with a pair of flanged screw-threaded members 24, 24, which are connected to the arm 22 in such a manner that the relative positions of the slide and the needle 18 may be adjusted. The arrangement is such that as the slide 21 is operated to open or close the air inlet to the

apparatus, the spindle 20 is also raised or lowered to move the needle 18 relatively to the jet orifice 17. The spindle 20 slides within a sleeve 25 secured to the base of the apparatus and diametrically of the air passage therethrough, the sleeve 25 being formed longitudinally with a fuel outlet the effective area of which is controlled by the movement of the spindle 20, the fuel outlet being in the form of a comparatively narrow slot 26 which is illustrated more particularly in Figure 4 of the drawings. The fuel is supplied to the jet 17 by means of the fuel chamber 9 and maintained, for example by means of a float, at or about a level coincident with the jet orifice. The jet 17 is surrounded by a wall 27 which forms part of the jet chamber 16 to which atmospheric air is admitted under the control of the rotary valve 14. The wall 27 is perforated at the lower end as at 28.

In order to vent the depression at all times other than the period during which fuel is required to flow, the rotary valve 14 is mechanically operated through driving connection 30 in timed relation to the engine. The valve or rotor 14

25 is in the form of a sleeve and is mounted within the housing 13 and controls a venting or pressure breakdown orifice 31 to the conduit 15 in communication with the jet chamber 16 enclosing the fuel orifice 17. The venting orifice 31 is in the form of a slot 32 as indicated in Figure 1 and it has been found advisable to make the opening and closing period of the slot operative over the minimum number of degrees, i. e. crank angle degrees. The rotor 14 is connected

35 by means of a spindle 33 to a known form of governor 34 which actuates a push-rod 35 contacting one end of arm 36 pivoted to the end of the casing 13. The arm 36 is integral with one end of an operating rod 37, the other end of

40 which is operatively connected with the slide 21 by means of an adjustable member 38. The operating rod 37 is held by a spring 40 which tends to keep the slide 21 in the closed position. Upon

rotation of the rotor 14 the governor 34 is brought 45 into operation to move the push-rod 35 and eventually raise the operating rod 37 to open the slide 21. Such an operation, however, is ineffective until the usual throttle pedal or other control mechanism has been actuated to rock a

50 pivoted lever 41 having an arm 42 which bears upon the aforesaid operating rod 37. Upon removal of the arm by a pull on the lever 41 in the direction of the arrow indicated in Figure 1, the operating rod 37 will be permitted to move

55 under the control of the governor 34 but not otherwise. In other words, the opening of the apparatus slide will be controlled by the engine speed which controls the governor but the closing of the said slide will be controlled by the

60 throttle pedal which positively returns the operating rod through the medium of the lever 41 and arm 42. The operating rod, however, may be moved positively for a determined distance to a predetermined position whereby the initial

65 acceleration is effected positively and this initial movement is conveniently effected by means of a cam 39 which bears on the operating rod and raises it a short distance as the lever 41 is rocked to the right in the direction of the arrow.

70 Figures 5, 6 and 7 illustrate an application of the invention in which a rotary valve 14 is mounted within a valve casing 13 and controls a pair of conduits 43, 44, one of which leads to the jet chamber surrounding the jet 17 and the other to the upper part of the fuel chamber 9 or other

supply line which may be vented to atmosphere, the rotor 14 being recessed as at 45 to enable the passages 43 and 44 to be placed in communication with each other.

With such an arrangement, and assuming the conduits 43 and 44 are closed as shown in Figure 5, the continued rotation of the rotor 14 will place both conduits 43, 44 in communication with each other and thereby transfer the pressure existing in conduit 43 to conduit 44 and create a balancing effect upon both sides of the jet orifice, thereby bringing fuel flow to a positive halt and in a completely steady and stable condition. Having reached this condition, continued rotation of the rotor will open both conduits to atmosphere to place the fuel flow line under approximately atmospheric pressure conditions. The fuel chamber 9 is vented at 46.

Comparative tests show the following results where the invention is applied to a standard internal combustion engine:

	Fuel consumption	Maximum H. P.
Single cylinder internal combustion engine of 8 H. P. with standard carburettor.	0.9 pints per B. H. P. per hour.	8
Identical engine with apparatus according to the invention.	0.5 pints per B. H. P. per hour.	11

The use of a standard carburettor limits the fuel available to petrol whereas with apparatus in accordance with the invention heavier fuels such as kerosene can be used in addition to petrol and will give approximately the same power output for the same consumption of fuel.

For convenience the present invention has been described with the main components of the apparatus assembled as a unit, but it is to be understood that each of the component parts could be separated, for example the rotor could be placed at any convenient position adjacent the accessory driving shaft by which it may be driven; the fuel chamber may be at any convenient part of a motor vehicle and the mixing and metering apparatus may be directly attached at any point of the induction system or in communication therewith. Furthermore, the breakdown may be effected at either side of the fuel orifice—breaking down on the entry side would permit fuel flow—breaking down on exit side would prevent fuel flow. Breaking down at the entry side would be effected, for example, at the fuel chamber by

placing the latter under a pressure equal to the exit side of the jet orifice.

What I claim and desire to secure by Letters Patent is:

1. Apparatus for controlling the flow of fuel to an internal combustion engine comprising an orifice for the supply of fuel to an air inlet to the engine under the action of engine suction, a jet chamber in communication with said air inlet through said fuel orifice, and means operable in timed relation to the rotation of the engine to vent said jet chamber for a predetermined period within the ambit of the suction stroke of the engine without affecting the rate of air flow to said engine.
2. Apparatus for controlling the flow of fuel to an internal combustion engine comprising an orifice for the supply of fuel to an air inlet to the engine under the action of engine suction, a jet chamber in communication with said air inlet through said fuel orifice, and a valve operable in timed relation to the rotation of the engine to vent said jet chamber for a predetermined period within the ambit of the suction stroke of the engine without affecting the rate of air flow to said engine.
3. Apparatus for controlling the flow of fuel to an internal combustion engine comprising an orifice for the supply of fuel to an air inlet to the engine under the action of engine suction, a jet for the supply of fuel to said air inlet through said orifice, and means operable in timed relation to the rotation of the engine to effect a subatmospheric equalization of the air pressure acting on the fuel entering said jet with the air pressure acting on the outlet of said jet for a predetermined period within the ambit of the suction stroke of the engine.
4. Apparatus for controlling the flow of fuel to an internal combustion engine comprising an orifice for the supply of fuel to an air inlet to the engine under the action of engine suction, a jet chamber in communication with said air inlet through said fuel orifice, a fuel chamber communicating with a jet in said jet chamber and having an overlying vapor space, and means operable in timed relation to the rotation of the engine to effect intercommunication between the vapor space of said fuel chamber and said jet chamber for a predetermined period within the ambit of the suction stroke of the engine.

WILLIAM DOUGLAS MARCHANT.
